Fig.-1

Fig.-3

Fig.-2

FIG. 1 is a front view of a door knocker or the like, showing my new design, the back thereof being plain and unornamented;

FIG. 2 is a top view thereof, and

FIG. 3 is a side view thereof.

The essential features of my design reside in the portions shown in solid lines, conventional printed matter being shown in broken lines.

I claim:

The ornamental design for a door knocker or the like, as shown and described.
